UNITED STATES PATENT OFFICE.

BERTIL VON PHILP, OF PHILADELPHIA, PENNSYLVANIA, ASSIGNOR OF TWO-THIRDS TO J. WIGGANS THORN, OF TRENTON, NEW JERSEY, AND HARRY L. OGDEN, OF PHILADELPHIA, PENNSYLVANIA.

BRAKE FOR CARS.

SPECIFICATION forming part of Letters Patent No. 729,658, dated June 2, 1903.

Application filed January 22, 1903. Serial No. 140,060. (No model.)

To all whom it may concern:

Be it known that I, BERTIL VON PHILP, a citizen of the United States, residing in the city and county of Philadelphia, State of Pennsylvania, have invented a new and useful Improvement in Brakes for Cars, of which the following is a specification.

My invention consists in an electric car-brake which is adapted to be applied to the motor thereof.

It further consists in providing means for the adjustment of the brake to allow for wearing away of the frictional parts.

It further consists in novel details of construction, all as will be hereinafter fully set forth.

Figure 1 represents a vertical sectional view of a portion of a hub connected with an armature-shaft of the casing therefor and the brake in position, said section being taken at a point represented by line *x x*, Fig. 2. Fig. 2 represents a horizontal sectional view on line *y y*, Fig. 1. Fig. 3 represents a plan view of one-half of the mechanism.

Similar letters of reference indicate corresponding parts in the figures.

Referring to the drawings, A designates a hub which is attached to an extension of the armature-shaft of the car-motor, said hub being provided with the ears or lugs B and extends into a casing C, which is suitably connected to the motor-casing in the present instance by means of screws passing through the openings D, said casing C being provided

35 with the lugs or extensions E.

F designates disks which are suitably provided with noses or extensions G, which are adapted to fit into or extend between the projections E on the casing, while interposed between each of these disks F are disks H, which are provided with extensions or noses J, which are adapted to enter or be seated between the lugs or projections B on the hub, it being seen that in this manner the disks F and H 45 alternate with respect to each other and are placed one upon the other.

K designates a transmitter which rests upon the uppermost one of the disks, and situated above said transmitter is a washer L, having 50 a central opening, said washer being suitably

connected with the casing C and with a box M by means of the screws N, said box M having a chamber P therein, the washer L forming the bottom or lower wall of said chamber, said box M also having a central bore Q, in which is situated a spring R, which is adapted to bear against the transmitter K, the opposite end of said spring bearing against a gland S, which is held in position, with respect to the casing, by means of the screws 55 T and nuts U.

V designates a coil situated within the chamber P, formed in any suitable manner and which is of such strength as to overcome the power of the spring when the current is 60 applied.

The operation will be readily understood. When the current is applied, the coil operates to draw the transmitter K away from the disks, whereby the same can move freely with respect to each other—that is, the disks H, which are keyed to the hub A, are permitted to turn therewith, whereby the motion of the motor is permitted; but as soon as the power is shut off the spring R immediately actuates 70 the transmitter in the opposite direction and presses the disks F and H together, thus preventing the rotation of the same and stopping the movement of the hub, and consequently the motor. If desired, I may connect the operating of the brake with a switch, in which event I employ the wires W, which connect with a suitable switch, so that the brake can be operated as desired.

It will be evident that various changes may 75 be made by those skilled in the art which will come within the scope of my invention, and I do not, therefore, desire to be limited in every instance to the exact construction herein shown and described.

Having thus described my invention, what I claim as new, and desire to secure by Letters Patent, is—

1. In a device of the kind specified, a disk suitably connected with the armature shaft or 95 motor, a second disk suitably connected with a stationary portion, a transmitter, a spring bearing directly upon said transmitter, a coil adapted to overcome the force of the spring when the current is applied, whereby the 100

disks can rotate with respect to each other and means interposed between said coil and the transmitter.

2. In a device of the kind specified, a disk 5 suitably connected with the armature shaft or motor, a second disk suitably connected with a stationary portion, a transmitter, a spring bearing directly upon said transmitter, an electromagnet adapted to overcome the force 10 of the spring when the current is applied, whereby the disks can rotate with respect to each other, a washer interposed between said electromagnet and the transmitter, means securing said washer between the adjacent ends 15 of the casing of said magnet and of said disks, and means for varying the tension of said spring.
3. In a device of the kind specified, a casing, a hub extending thereinto, disks having ex- 20 tensions fitting between projections on the inner wall of said casing, disks having extensions disposed between lugs on the hub, a transmitter covering the end of said hub and bearing against the adjacent disk, a box hav- 25 ing a chamber, a coil therein, a spring disposed centrally within said box and bearing directly against said transmitter, means in-

terposed between said transmitter and coil and means interposed between said box and casing and having an aperture through which 30 said spring works.

4. In a device of the kind specified, a casing having inwardly-projecting lugs, a hub having lugs within said casing, disks having extensions fitted between the lugs of the casing, 35 disks having extensions fitted between the lugs of the hub, a transmitter covering the inner end of the hub and bearing directly against the adjacent disk, a washer surrounding said transmitter and bearing against the 40 casing, a box bearing against said washer and having central bore, a spring within said bore bearing directly against the center of the transmitter, means connected with said box and bearing directly against the spring, 45 means for adjusting the tension of said spring and a coil within said box and adapted to overcome the power of the spring when the current is applied.
